PRESSURE TUBE SALVAGE APPARATUS
AND METHOD

Gilbert D. Hendry, 35 Burcrest Drive,
Toronto, Ontario, Canada
Filed May 7, 1965, Ser. No. 453,987
7 Claims. (Cl. 114—50)

This invention relates to the salvage or refloating of sunken vessels and is specifically directed to a novel method and apparatus whereby the stability and ascent of a vessel during the refloating process may be more readily and accurately controlled than heretofore possible.

Many proposals have been put forth and tested respecting the introduction of compressed air or foamant material into the hull of a sunken ship but while such proposed expedients have achieved a degree of success, major problems still exist in their use.

One of the aforementioned problems resides in containing the compressed air or foamant in the vessel and in order to preclude escape of the latter, extremely expensive and frequently difficult underwater preparatory work is required to seal hatches, ventilators and damaged areas. In instances where a ship has gone down in deep water, diving operations are limited and are often rendered hazardous by tricky and powerful currents. All this adds up to very high costs with limited guarantee of eventual success.

In an attempt to overcome the problems faced in completely sealing the ship, inflatable containers have been and are being used to contain the buoyant agent. These containers, usually provided with an outer protective mesh covering are located within the ship and then compressed air or foamant is pumped in. At first blush, this appeared to be a solution but it has been found that a high percentage of the containers are ruptured in use, either by projections within the ship or by pressure differential unbalance as the ship rises through the varying pressure levels of the surrounding water. As the flexible containers are quite expensive, it is obvious that this "solution" is not entirely satisfactory.

It has further been proposed to pump liquid foamants into the hull of a sunken vessel such that they commence to foam within the hull. Here again, the problem of extensive under-water preparation to prevent escape of the liquid foamant prior to complete formation of the foam structure is encountered.

With these prior art methods there has also prevailed the difficulty of ensuring that the ship rises in a stable manner, that is, the ship does not tend to roll or pitch about its longitudinal or lateral axes. It is of course, almost impossible to completely seal the hull of a sunken ship, especially when the latter has been damaged to any extent and thus salvage operators on the surface have no way of determining whether or not the buoyancy forces exerted on a ship are evenly distributed at any given time. Until such time as the ship has risen to a critical level, there can be little or no lift or attitude control exercised. By the time the situation becomes apparent, there is only a very limited time to effect some form of stabilizing action before the ship rolls or pitches over. In short, use of compressed air or materials difficult to contain are unpredictable and have generally been found unsatisfactory in salvage attempts.

It is an object of this invention to provide a novel salvage method and apparatus which minimizes preparatory under water work thus considerably facilitating the salvage of vessels, especially those lying in deep water and subject to strong currents.

It is a further object of this invention to provide a novel salvage method and apparatus wherein the buoyant materials may be recovered for re-use.

2

A still further object is to provide a salvage method and apparatus wherein control of the ship's attitude during its ascent is more predictable than in presently known methods.

5 The foregoing objects are achieved by driving bundles or charges of solid buoyant material into the ship such that hatchways and other openings merely require the placement of perforate grids thereover in order to preclude escape of the charges. It will be readily apparent that such grids may be handled under water with far greater facility than large, heavy patch plates and the like.

10 In order to ensure more or less even distribution of the charges within the ship, water jets may be employed to create turbulence in the ship's interior. Further, any undamaged ballast tanks or the like may be partially blown or evacuated to a degree to a degree dependent upon the particular ship's attitude, area of damage and so on.

15 The invention will be more readily understood from the following detailed description taken in conjunction with the appended drawings wherein:

20 FIGURE 1, A schematic representation of the tube means assembled and in operative position with respect to a salvage vessel and a sunken ship.

25 FIGURE 2, An enlarged view of the pump and feed sections of the tube means and

30 FIGURE 3, A detail of the gate actuating means.

35 As previously noted, one of the prime advantages of this invention resides in the substantial savings obtained in underwater preparation of the vessel prior to the actual operation of inserting the buoyant material.

40 In some instances it will be found possible to lower prefabricated grill structures into position over hatches and other openings for welding or otherwise securing thereto. Such grills may be of coarse "mesh," the openings therein being of a size sufficient to just preclude escape of the charges of buoyant material.

45 In other situations, suitable lengths of structural steel members may be lowered into position over any openings or "weak-spots" such as hatches etc. and secured in a charge-confining arrangement by any of the well-known expedients.

50 Generally speaking, the installation of the charge-retaining structure and the type or system to be used will be ascertained following a study of the type of vessel involved, the depth of water and the currents involved. Naturally, conditions will vary considerably from case to case and it is considered unnecessary to enter into a prolonged discussion herein concerning this point. To those skilled in this field, the appropriate steps necessary in any given situation to affix the required grills in position will be readily apparent.

55 60 65 70 75 A further important consideration is the type of buoyant material to be used. In many instances, the selection will be affected by the salvage location and availability of materials, however with this novel method and apparatus, considerable latitude is granted. Generally, any more or less solid, buoyant material may be used. In each case, the material is cut to form packages or charges of a size governed only by the dimensions of the delivery tube and handling considerations on board the salvage ship together with the effects of charge size upon distribution within the sunken vessel.

75 It will be appreciated that the materials used herein are also "salvaged" with the ship and may be used again whereas with most prior salvage methods, the materials are not only useless for re-application in further salvage work but also for any other purpose. This instant invention is thus seen to present considerable savings as regards preliminary driving operations and as regards the cost of material.

Referring to the drawings, FIGURE 1 illustrates one embodiment of the present invention including tube means generally designated by the numeral 10 attached to a loading deck 11 which, in turn, is flexibly connected to a salvage vessel 12, and extending downwardly therefrom through an adaptor funnel 13 into a sunken vessel 14. The flexible connection between the loading deck 11 and the salvage vessel 12 may comprise some form of chain or like conveyor means suitable for feeding buoyant material from the salvage vessel to the said loading deck. Such a flexible connection isolates the tube means from undesirable movement of the ship.

It is also feasible that in sheltered areas where reasonably secure anchorage is obtainable for shipping, the tube means assembly could be incorporated in a specially constructed salvage vessel. Such a vessel would preferably have ballast tanks by means of which the vessel could be lowered in the water for greater stability. The tube means would be independently suspended through a well formed in the salvage vessel's hull, the well being located as close as possible to that point about which the vessel would normally pivot to some extent while at anchor. In this manner, undesirable movement of the tube means would be obviated to a satisfactory degree.

It will be obvious that insofar as is possible, movement of the tube means in operation should be precluded and since, as will later be described, the tube means is provided with controllable buoyant support means, motion of the salvage vessel will be dissimilar to that of the tube means and thus a rigid connection between the two is undesirable.

As best seen in FIGURE 2, the bottom end of the tube is preferably located as close to the bottom of the sunken vessel as possible to facilitate dispersal of charges of buoyant material 15 in the confines of the ship and further to preclude insofar as possible premature fouling of the tube exit.

The tube means 10 comprises a plurality of tube sections of preferably rectangular cross-section, although other suitable cross-sections may be used, connected together by means such as flanged couplings and gaskets such that a portion to be located under water may be sealed at will by valve or gate means. The tube means includes a loading section 16 having a loading hatch 17 through which the charges 15 are inserted into the tube means. In addition, loading section 16 carries a ram deck 18 upon which is mounted a motorized hoist 19 operable, through cable means 20 and pulley arrangement 21, to raise and lower a dead-weight plunger or ram 22. It should be noted that the cross-sectional dimensions of the charges 15 should be such as to just permit the charges to slide through the tube means without undue tilting relative to the longitudinal axis of said tube means. In the drawings, the lateral dimensions of the charges are shown somewhat smaller in the interest of clarity.

Immediately below loading section 16 and connected in end to end relation thereto is a buoyancy compensating means comprising a water-receiving tank section generally designated by numeral 23. Section 23 comprises a tube 24 having the same internal dimensions as section 16 and also having secured thereto in surrounding relationship an annular water tank 25 for a purpose to be hereinafter described.

Coupled to the lower end of section 23 is a buoyant section generally designated by the numeral 26 and comprising a tube section 27 with a buoyancy tank 28 of any suitable configuration connected thereto in surrounding relationship. The function of the buoyancy section 26 is to support the tube means 10 in an operative stable position relative to the loading deck 11 and the sunken vessel 14. In order to adjust the buoyancy of the tank 28, to suit any particular circumstance or situation, an air valve 29 and water valve 30 are provided. Air valve 29 permits "blowing" of the buoyancy tank by com-

pressed air while water valve 30 permits inflow of water to the buoyancy tank. Thus, by blowing compressed air through air valve 29 and forcing water out of water valve 30, or, by releasing air through air valve 29 and admitting water through water valve 30, the buoyant force exerted by the tank 28 upon the tube means may be readily and accurately controlled.

Below the buoyant section 26 is located a plurality of intermediate tube sections 31, the number required varying according to the depth of any given operation. The intermediate sections may be of any suitable, readily handled lengths and of course, have the same internal dimensions and configuration as the other sections noted hereinbefore.

15 Coupled to the lowermost intermediate tube section, again by any suitable well known tube coupling expedient, is a pump section 32 comprising a tube member 33 to which is connected a submersible pump 34 communicating with the interior of tube 33. Also connected to tube 33 is a flooding valve 35, the function of which will be hereinafter described.

At its lower end, pump section 32 is slightly enlarged in cross-section to accommodate a pivoted gate member 36 operative to selectively close off or open the passage 25 through pump section 32. The mechanism by which this gate 36 is operated may be one of many well known expedients. In the illustrated embodiment, the gate 36 is shown as being operated by a hydraulic ram means 37 and 37'; but, obviously, there are many other known and suitable methods or expedients which could be used without departing from the spirit and scope of the invention herein disclosed. All that is required is a gate member which may be swung as desired from an inoperative position to a position positively sealing one portion of the pump section from another and, further, a gate member, which, in said inoperative position, will in no way obstruct passage of charges 15 through the pump section 32. In the embodiment shown, the gate 36 is pivoted at one end thereof to a fixed portion of the tube means as at 36a. Hydraulic ram means 37 and 37' are pivotally mounted as at 37a to exterior surfaces of the tube means and the reciprocating piston elements of the ram means are pivotally connected to pins 36' extending from the gate through curved slots 32' in the enlarged portion of section 32. Thus, on retracting the said piston elements, the gate 36 is forced onto sealing engagement with gasket means to effectively seal the upper portion of the pump section from the lower portion thereof. The operation of pump section 32 will be understood as the description proceeds.

50 The last section of the tube means 10 comprises a feed section 38 having an enlarged portion 39 adjacent the upper end thereof for mounting some form of non-return means 40 within the tube means. This latter means as shown, includes a pair of complementary pivoted plates 41 and 42 biased to normally lie in co-planar edge-abutting relationship to prevent passage of charges 15 upwardly into pump section 32. The abutting edges of plates 41 and 42 are preferably serrated or castellated for mating registration with one another.

60 Immediately above the non-return means 40 and secured to the inner surface of the feed section 38 is located a stop means 43 having internal dimensions of a size sufficient to permit the charges 15 to pass therethrough and comprising two or more bar members connected to said inner surface. Further, the upper surface of stop means 43 is tapered as at 44, to guide the charges through the stop means and thus facilitate passage of said charges. The function of stop means 43 is to arrest or terminate the downward "stroke" of the dead-weight plunger 22.

65 The vertical distance between the plunger stop means 43 and the non-return means 40 should be minimal to ensure that the plunger forces all the charges past said non-return means. It will be obvious that if even one buoyant charge were to remain in the pump section, the

gate 36 would be unable to function properly and costly delays would arise.

To preclude any possibility of buoyant charges remaining in the pump section, the lower end of the plunger 22 is reduced such that the reduced portion 22a passes the stop means in ramming the buoyant charges clear of the non-return means 40 and shoulder 22b abuts the stop means to arrest further downward movement of the plunger.

After a sunken vessel has been located and all hatchways and openings have been suitably secured by means of perforate grid means, adaptor funnels 13 are located and fixed in strategic positions in the deck or hull providing inlets to suitable compartments for the buoyant charges. The adaptor funnels 13 are preferably provided with non-return gate or valve means 47 similar to the non-return means 40 and for the same purpose. Further, abutment means 48 are adjustably connected to the lower end of feed section 38 to centre same with respect to the adaptor funnel and to provide additional support to that obtained by the buoyancy section.

The depth of the vessel is ascertained and the tube means is assembled accordingly (FIGURE 1), the required number of intermediate sections being used to ensure that the bottom end of the feed section 38 is spaced from the bottom of the vessel a distance just sufficient to permit the charges to leave the tube means and disperse within the compartments of the sunken vessel.

The tube means is then positioned over an adaptor funnel 13 and the buoyancy tank is flooded until the tube means sinks into the desired position, as best seen in FIGURE 2, and the ratio of air to water in the buoyancy tank is such as to substantially provide a state of equilibrium such that the tube means is supported primarily by said buoyancy tank and to a slight degree by the adaptor funnel.

With the tube means assembled and in operative position, gate member 36 is closed and flooding valve 35 is also closed. The submersible pump 34 is then started and commences to pump water out of that portion of the tube means above the gate member 36 and into the water tank 25 through line 45. The water pumped from the tube means is fed back into the water tank 25 in order to substantially maintain the equilibrium of the device.

As the upper portion of the tube means is being pumped out, charges of solid buoyant material having a specific gravity less than 1.0 and preferably in the range of 0.2 to 0.1 are inserted in the tube means through the loading hatch 17 such that when the water level reaches the suction level of the pump 34, the upper portion of the tube means is substantially full of buoyant material and the dead-weight plunger is then lowered until it engages same. The flooding valve 35 is then opened and permits return of the water from water tank 25 to the tube means above gate member 36 through line 46 to substantially equalize pressure on opposing sides of the gate member 36 and facilitate opening thereof with the result that the buoyant material is forced or rammed down the tube means by the plunger and ejected from the feed tube into the compartment of the vessel. In order to ensure rapid return of the water from water tank 25, air pressure is preferably applied to tank 25 through a pipe P which may be connected to an air compressor aboard the salvage vessel.

In instances where salvage operations are to be carried out in relatively shallow waters, the dead-weight of the tube means may be sustained by the sunken vessel since only a few sections will be required to attain the necessary depth and in such instances, while the buoyant section will still be effective to stabilize the tube means and will be retained as part of the assembly, the water-receiving tank section is not required. In short, there will be no necessity for buoyancy compensating means during pumping of the tube means.

To ensure that the plunger 22 maintains a substantially vertical attitude at all times during the ramming operation and during withdrawal, the said plunger should be of a

length somewhat greater than the depth of the enlarged portion of pump section 32. In this manner, the plunger will always be guided, at least in part, by the tube means and displacement from the vertical will be precluded to avoid jamming. The charges 15 must be of similar length for the same reason.

When the plunger 22 bears on the stop means 43 it is hoisted by means of hoist 19 and the non-return means 40 closes to preclude the possible return of some of the buoyant material from the feed section of the tube means to the pump section where it would jam the operation of the gate 36 as hereinbefore mentioned.

The foregoing cycle is then repeated, both at the same location and in the other preselected locations until such time as the positive buoyancy within the vessel is sufficient to overcome the dead-weight thereof including any other forces tending to produce negative buoyancy.

During the cycling of the tube means, it may, in some cases, be found expedient to pump water into the compartments of the vessel to create turbulence therein and to effect a more rapid and efficient distribution of the buoyant material, and further, in instances where ballast tanks are undamaged, it may sometimes be found feasible to "blow" such tanks by compressed air means.

The buoyant material used may be one of several types such as the expanded polyurethane plastics, cork, foam-glass or the lighter woods such as cord-wood or undressed balsa logs. As will be well appreciated by those skilled in the art, the only limiting factor of any significance to be considered in the choice of material would be the pressure conditions prevailing in any given salvage attempt.

Upon reaching that point in a salvage operation wherein the vessel begins to rise, the equipment may be readily withdrawn from the vessel merely by reversing the insertion procedure that is, the buoyancy tank is "blown" as required, whereupon the apparatus or equipment rises, the lower portion of the tube means thus clearing the vessel which may then ascend under such control as is normally applied at this stage.

With respect to the means used in delivering the material through the tube means, namely the dead-weight plunger, it is pointed out that other expedients such as chain-link or belt conveyors, compressed air or similar methods and apparatus could be used instead of that illustrated and described herein.

Many changes and modifications will be apparent to those skilled in this field after reading this disclosure without departing from the spirit and scope of the invention.

What I claim as new and desire to protect by Letters Patent of the United States is:

1. In apparatus for use in the salvaging of a sunken vessel, the combination comprising, tube means including tubular members secured in end to end engagement to extend from a surface structure to a location within a sunken vessel; charge delivering means located at the upper end of said tube means operative to deliver preformed charges of buoyant material down said tube means and into said sunken vessel; said tubular members including a pump section comprising a tube having a submersible pump means attached thereto and communicating therewith, a gate member pivotally mounted within said tube and operative to close said tube to permit the submersible pump to pump out water from a portion of the tube means above said gate member to facilitate loading of the preformed charges into the tube means; controlled buoyancy means connected to said tube means and operable to stabilize said tube means in submerged operative position.

2. The combination as defined in claim 1 wherein said controlled buoyancy means comprises a buoyant section, said buoyant section comprising a further tube having secured thereto in surrounding relationship a buoyancy tank means, said last mentioned means having an air valve and a water valve therein operable to control the air to water ratio in said buoyancy tank such that the buoy-

ancy section fully supports said tube means in operative position.

3. The combination as defined in claim 2 and further including a buoyancy compensating tank section connected superjacent the buoyant section and including an annular water-receiving tank; means extending from an outlet of said submersible pump to the water-receiving tank to conduct the water pumped from said portion of the tube means to the tank to substantially maintain the tube means in a state of equilibrium.

4. The combination as defined in claim 3 and further including pipe means extending from said water-receiving tank to the said portion of the tube means, and compressed air means selectively operable to force the pumped water from the water-receiving tank through said pipe means and into said portion of the tube means to equalize pressure on opposite sides of the gate member.

5. The combination as defined in claim 1 wherein said gate member is pivotally mounted at one end thereof to an inner surface of said tube; hydraulic ram means including piston means, said hydraulic ram means being pivotally mounted on the exterior of said tube and said piston means being pivotally connected to pivot pins extending from the edges of said gate member and projecting outwardly of the tube through curved slots formed in said tube.

6. The combination as defined in claim 1 wherein said charge delivering means comprises a dead-weight plunger;

means mounted on said surface structure, operable to raise and lower said dead-weight plunger.

7. In apparatus for use in salvaging a sunken vessel, the combination comprising, tube means operable to extend from a surface structure to a location within the sunken vessel; buoyant means operable to support said tube means in operative location; sealing means in the tube means and operable to seal off an upper portion of said tube means from a lower portion thereof; pump means communicating with the upper portion of said tube means and operable to remove water therefrom to facilitate the loading of buoyant charges therein; buoyancy compensating means adapted to maintain said tube means in substantial equilibrium during pumping of the water from said upper portion of the tube means; charge delivery means located in operative relationship with said tube means to deliver buoyant charges through the tube means to the interior of the sunken vessel.
